FOUNTAIN PEN

Ferdinand M. Pisculli, Yonkers, N. Y.

Application April 28, 1945, Serial No. 590,799

2 Claims. (Cl. 120—47)

1

This invention is a fountain pen of the type in which a piston or plunger is utilized to draw ink into an ink reservoir from an outside source.

One of the objects of the invention is to provide a fountain pen of the character mentioned in which the parts are so arranged that they may be readily disassembled for repair and cleansing purposes and which may be quickly and easily reassembled by the user. A further object of the invention is to provide a plunger type fountain pen so constructed and arranged that the plunger may be quickly moved within the ink reservoir while filling the latter or ejecting ink therefrom. A further object is to provide a pen of the type mentioned so constructed and arranged that the piston may be reciprocated without the necessity of any portion of the piston stem being moved into or out of the pen barrel, so that the overall length of the pen remains unchanged during movement of said piston.

The invention will be hereinafter fully set forth and particularly pointed out in the claims.

In the accompanying drawing—

Figures 1, 2 and 3 are longitudinal sectional views, with parts broken away, illustrating details of a fountain pen constructed in accordance with the invention.

Figure 4 is a detail sectional view illustrating the pen barrel.

Figure 5 is a detail longitudinal sectional view illustrating the guide bushing and the anchoring plug.

Figure 6 is a detail sectional view illustrating the piston sleeve.

Figure 7 is a detail view illustrating the piston actuator stem.

Fig. 8 is an end elevation of the actuator stem.

Referring to the drawing, 10 designates a tubular body which may be constructed of any desired material, but it is preferred to employ any one of the well known synthetic resins for this purpose, so as to combine lightness of weight with maximum strength. Said barrel provides an ink reservoir 11, which is closed at one end by an integral pen-section 12. Said extension is provided with a port 13 for conducting ink to the ink feeding member 14, which projects from the outer end of the pen section 12, so as to supply the pen point 15 in the usual and well known manner.

Located within the barrel 10 is a tubular guide member 16, which is internally threaded at one end. Said guide member is removably anchored within said barrel by means of a head 17, having a reduced threaded portion 18 which extends into

2

the adjacent end of said guide tube, and engages the internal threads therein. The body portion 18a of said plug is of a size to frictionally fit within the adjacent end of the barrel 10, so as to firmly, but removably anchor the guide tube 16 in its proper position within the barrel 10. Said head also has an annular flange 17a which abuts the adjacent end of said barrel and has approximately the same outside diameter as that of the latter.

Slidably mounted within the guide tube 16 is a tubular piston stem 20, closed at one end as indicated at 21, said closed end being that which is extended into the ink reservoir 11. The closed end 21 is provided with an opening, to accommodate the shank of a screw 22, which secures the piston head 23 to said stem. The bore 24 of the piston stem is provided with screw threads which are complementary to external threads 25 on an actuator stem 26, which latter extends through and is slidably mounted in the anchoring head 17. The outer end of said actuator stem is provided with an enlarged head 27, for convenient manual rotation of said stem. The complementary threads of the actuator stem and the piston stem are preferably of such pitch as to cause quick travel of the piston stem and its piston, in either direction by slight rotative movement of the actuator stem. The head 27 and the actuator stem 26 are normally held against separation by means of a stop pin 28. If desired, an end cap 29 of the usual type may be employed, which may be selectively engaged with the head 17 of the pen section 12. For example, the pen section 12 may be provided with external screw threads which are complementary to an internally threaded portion of the cap 29, so as to safely cover the pen point, said cap having an edge portion extended beyond its threaded portion to frictionally engage the flange 17a.

In practice, when it is desired to fill the ink reservoir 11, the head 27 is manually rotated in the direction to cause the piston, due to the reaction of the threaded engagement of the piston stem and the actuator stem, to move toward the pen section. The stem 26 is held against axial movement by the pin 28. The pen section is then dipped into an inkwell or other suitable reservoir, and then by reversing the rotation of the head 27, the piston will be moved inwardly, drawing in ink with it. This reverse movement is arrested by the pin 28 when the reservoir has received the proper amount of ink and before the piston head may jam against the head 17. The pen will then be ready for use. In this connec-

tion it is to be understood that in Figures 1, 2 and 3 the parts are shown in positions occupied during the filling operation and it will be understood that when the reservoir is filled plunger 23 will have been moved to the limit of its travel to the right as viewed in the drawings, and that the last mentioned position is maintained until it is necessary to refill the reservoir.

The advantages of the invention will be readily understood by those skilled in the art to which it belongs. For instance, it will be observed that a piston type fountain pen is provided which is constructed of few parts, all of which are so arranged that the pen may be assembled or disassembled by its user, without the necessity of calling upon expert aid for the purpose. Another advantage is that a quick acting piston is provided, and the necessity of having a piston stem which must reciprocate in and out of an end of the pen barrel is avoided.

Having thus explained the nature of the invention and described an operative manner of constructing and using the same, although without attempting to set forth all of the forms in which it may be made, or all of the forms of its use, what is claimed is:

1. A fountain pen of the character described having in combination a tubular barrel providing an ink reservoir, a pen section closing one end of said barrel and in communication with said reservoir, a tubular guide member located within and slidably engaging said barrel in spaced relation with respect to said pen section, said guide member being internally threaded at one end, an anchor head having sliding frictional engagement with the interior of the barrel and provided with a reduced threaded portion removably engaging the threaded portion of said guide member, a tubular piston stem slidably mounted within said guide and having a piston head located within said reservoir, and an actuator stem rotatively mounted within said head and telescoping with said piston stem, said ac-

tuator stem and said piston stem having complementary means for imparting axial movements to said piston stem while the actuator stem is being rotated.

- 5 2. In a fountain pen, a tubular barrel providing an ink reservoir, a pen section at one end of said barrel communicating with said reservoir, a tubular guide member snugly engaged within said barrel having one end spaced from said pen section, an internal thread at the opposite end of said tubular guide member, an anchor head to close the opposite end of said barrel and said tubular guide member, a reduced annular threaded portion on the inner end of said head to engage with the threads of said tubular guide member, an annular shoulder adjacent to said threaded portion abutting the adjacent end of said guide member and frictionally engaging within the barrel end, said anchor head having an axial opening therein, a tubular piston slidably engaging within said tubular guide member and having one end disposed in said reservoir, threads on the interior surface of said tubular piston, and a threaded actuator stem rotatably mounted in the axial opening in said anchor head with its threads engaged with the threads of said tubular piston.
